(57) **CLAIM**

The ornamental design for a hair removal apparatus, as shown and described.

DESCRIPTION

FIG. 1 is a front perspective view of a hair removal apparatus of the present invention showing our new design; FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines illustrate portions of the hair removal apparatus and form no part of the claimed design.

1 Claim, 6 Drawing Sheets
